UNITED STATES PATENT OFFICE.

LEONARD HAGGBLOM, OF LOS ANGELES, CALIFORNIA.

INITIAL SPARKER FOR GAS-ENGINE MAGNETOS.

1,137,609.

Specification of Letters Patent. Patented Apr. 27, 1915.

Application filed December 26, 1913. Serial No. 808,699.

To all whom it may concern:

Be it known that I, LEONARD HAGGBLOM, a citizen of the United States, residing at Los Angeles, California, have invented a new and useful Initial Sparker for Gas-Engine Magnetos, of which the following is a specification.

My object is to apply an attachment to the magneto of a gas engine so that when the engine is cranked the magneto will produce the initial spark to start the engine without the use of a battery; or to construct a magneto in accordance with the principles of my invention, and my invention consists of the novel features herein shown, described and claimed.

Figure 1 is a front elevation of a gas engine equipped with a magneto embodying the principles of my invention. Fig. 2 is a top plan view as indicated by the arrow 2 in Figs. 1 and 3. Fig. 3 is a side elevation as indicated by the arrow 3 in Fig. 2. Fig. 4 is a vertical section on a plane parallel with Fig. 3 as indicated by the lines 4—4 in Figs. 1, 2 and 5. Fig. 5 is an enlarged vertical cross section on the lines 5—5 of Figs. 2, 3 and 4. Fig. 6 is a vertical cross section on the lines 6—6 of Figs. 3 and 4. Fig. 7 is the side elevation of the spring casing and cam. Fig. 8 is a fragmentary perspective upon an enlarged scale of the locking device.

The magneto shaft 1 of the magneto 2 has a gear 3 upon its extreme forward end connecting with an idler 4 and this idler meshes with a driving gear 5 fixed upon the engine shaft 6. The magneto shaft 1 rotates in the same direction as the engine shaft 6.

The hub 7 is fixed upon the magneto shaft 1 and carries the mutilated disk 8, the periphery of the disk extending normally beyond the periphery of the hub. The disk is preferably formed integral with the hub. The portion 9 of the periphery of the disk 8 occupies substantially one third of the circumference and is concentric with the shaft 1. The portion 10 of the periphery of the disk 8 occupies substantially one third of the circumference of the disk and is eccentric to the shaft 1 there being a radial shoulder at the junction of the portion 9 to the portion 10 forming a locking tooth 11. The portion 12 of the periphery of the disk 8 is concentric to the shaft 1 upon a smaller circle, thus leaving a notch in which the stop tooth 13 operates. A sleeve 14 extends from the side

face of the disk 8 around the shaft 1. A hub 15 is loosely mounted upon this sleeve 14 and the gear 3 is fixed to the forward end of this hub. The inner end of the hub 15 is bored out to form the spring casing 16 and the clock spring 16^a is connected at its inner end to the sleeve 14 and at its outer end to the spring casing 16. The stop tooth 13 extends from the rear face of the spring casing 16 into the notch in the periphery of the disk 8 to limit the rotation of the hub 15 relative to the shaft 1. An eccentric 17 is formed upon the periphery of the spring casing 16.

The dash pot casing 18 is rigidly mounted upon the frame of the magneto and has a vertical piston chamber 19 normally open at the bottom. The piston 20 is mounted on the piston chamber and the locking dog 21 extends downwardly from the piston and serves as a stem for the piston. A cap 22 is placed against the lower face of the casing 18 and has a rectangular bearing through which the locking dog 21 reciprocates said locking dog being also rectangular so as to prevent rotation.

One half of the lower end of the locking dog 21 is a tooth 23 and in the plane of the disk 8 and is adapted to catch the tooth 11, and the other half 24 is a cam and is in the plane of the eccentric 17 so that when the eccentric rotates one third of a turn from its normal position the cam 24 rides upon the eccentric and the tooth 23 will be raised out of engagement with the tooth 11. The notch 12^a extends only half way through the disk 8, thus leaving a concentric rim 12^b upon which the tooth 23 rides over the notch.

Normally the spring 16^a is unwound to the limit of the notch in the periphery of the disk 8 and the tooth 13 stands in the position shown in Fig. 6 and the tooth 23 is in engagement with the tooth 11. When the engine is cranked the first movement of the engine shaft will rotate the gear 3, winding up the spring 16^a until the tooth 13 moves to the other end of the notch as indicated by the dotted lines in Fig. 6, and this operation will bring the high part of the eccentric 17 in position to raise the cam 24, thereby raising the tooth 23 out of engagement with the tooth 11 and raising the piston 20 in the piston chamber 19 thus allowing the tension of the spring 16^a to give a

quick rotation to the shaft 1, thereby generating a spark to ignite and start the engine.

A ring 25 is loosely mounted upon the hub 5 and a cam 26 extends from this ring in a position to pass under the pin 27 extending from the locking dog 21 so that when the cam 26 passes under the pin 27 the locking dog will be held up to avoid unnecessary 10 wear. A spring 28 holds the cam 26 normally out of use and a rod 29 provides means for operating the cam 26 and holding the locking dog out of use. This rod may be held in any suitable way and released when it is desired to start the engine.

The piston 20 controlling the locking dog 21 works like a dash pot with an air chamber. When the engine is started and the locking dog 21 thrown upwardly, it will 20 come down only gradually, being held by the air pressure, and the continued rapid rotation of the magneto shaft will keep the locking dog up, but when the magneto shaft comes to a standstill the locking dog will 25 slowly settle down into position to engage the tooth 11. In this manner the engine may be equipped with a magneto and started without the use of a battery.

It is obvious that a governor or a magnetic mechanism may be substituted for the dash pot without departing from the spirit of my invention, and that other details may be varied in many ways.

I claim:

35 1. The combination with a magneto shaft arranged with its axis extending along a different line from the axis of the engine shaft, of means operatively connecting said magneto shaft to said engine shaft to transmit a rotary movement from said engine shaft to said magneto shaft, a dash-pot, a member operating in said dash-pot and provided with a dog, means coöperating with said dog to hold said magneto shaft as the 40 engine starts, means to release said magneto shaft, and means to rotate said magneto shaft with an increased speed upon its release.

2. The combination, with a magneto shaft 50 having its axis extending along a different line from the axis of the engine shaft, of means operatively connecting said magneto shaft to the engine shaft to rotate said magneto shaft, a dash-pot, a member operating 55 within and projecting from said dash-pot, means coöperating with said member while

said member is extended to hold said magneto shaft as the engine starts, means to retract said member, and means to lock said member in the retracted position after the 60 engine has been fully started.

3. The combination, with a magneto shaft operatively connected with an engine shaft, of a dog having a tooth to hold the magneto shaft as the engine shaft starts, means operating upon a portion of said dog at one side of the tooth thereof to retract said dog and thereby release said magneto shaft, means to rotate said magneto shaft at an increased speed upon its release, and means to 65 retract said dog and maintain it in the inoperative position during the regular operation of the engine, said dog being provided with a part projecting laterally therefrom to coöperate with the last named means. 75

4. The combination, with a magneto shaft operatively connected with an engine shaft, of a dash-pot having a piston head and a stem the outer end of which has formed thereon a dog for holding the magneto shaft 80 as the engine shaft starts, means to retract said stem to release the magneto shaft, means to cause the magneto shaft to snap ahead to the extent of the lost motion to produce the initial spark to start the engine, 85 said means to retract said stem comprising a cam operating thereon against the opposition of the air in the dash-pot.

5. The combination, with a magneto shaft operatively connected with an engine shaft, 90 of a mutilated disk mounted on said magneto shaft in fixed relation thereto, said disk having a peripheral portion eccentric to the magneto shaft and terminating in a locking tooth, a dog to coöperate with said locking 95 tooth, a casing extending around said magneto shaft, said casing having a partial rotation with respect to said magneto shaft and being provided with a stop tooth which operates against a shoulder on said mutilated disk to hold the magneto shaft as the engine starts, a spring to cause said casing to rotate yieldingly with relation to said engine shaft, and means operatively connecting the engine shaft to said casing to 100 rotate the latter, said casing having upon its periphery means to release said dog to cause the magneto shaft to snap ahead.

LEONARD HAGGBLOM.
